94,446

DESIGN FOR AN AUTOMOBILE RADIATOR ORNAMENT OR SIMILAR ARTICLE

Harry A. Shaw, Huntington Woods, and Chris J. Klein, Detroit, Mich., assignors to Ternstedt Manufacturing Company, Detroit, Mich., a corporation of Michigan

Application November 24, 1934, Serial No. 54,153

Term of patent 7 years

To all whom it may concern:

Be it known that we, Harry A. Shaw and Chris J. Klein, both citizens of the United States of America, and residing respectively at 26725 Hendrie Avenue, Huntington Woods, in the county of Oakland and State of Michigan, and at 13315 Rochedale Avenue, Detroit, in the county of Wayne and State of Michigan, have invented a new, original, and ornamental Design for an Automobile Radiator Ornament or Similar Article, of which the following is a specification, reference being made to the accompanying drawing, forming part thereof.

Fig. 1 is side elevational view of an automobile radiator ornament or similar article showing our new design;

Fig. 2 is a top plan view of the same;
Fig. 3 is a front elevation of the same;
Fig. 4 is a section along the line 4—4 of Fig. 1.

As shown in Fig. 1 portions of the ornament are shaded to show a contrasting effect. The attachment portion of the ornament below the base of the ornament is concealed when the ornament is attached to the radiator shell and therefore is an immaterial part of the ornamental design.

We claim:

The ornamental design for an automobile radiator ornament or similar article substantially as shown and described.

HARRY A. SHAW.
CHRIS J. KLEIN.
